UNITED STATES PATENT OFFICE

103,629

DESIGN FOR A SAFE OR SIMILAR ARTICLE

Charles R. Davis, Rochester, N. Y., assignor of one-half to Charles H. Ineson, Rochester, N. Y.

Application November 19, 1936, Serial No. 66,022

Term of patent 14 years

To all whom it may concern:

Be it known that I, Charles R. Davis, a citizen of the United States, residing at Rochester, county of Monroe, State of New York, have invented a new, original, and ornamental Design for a Safe or Similar Article, of which the following is a specification, reference being had to the accompanying drawing, forming part thereof.

The drawing is a perspective view of a safe showing my new design.

I claim:

The ornamental design for a safe or similar article, substantially as shown.

CHARLES R. DAVIS.
